UNITED STATES PATENT OFFICE.

FRED I. NELSON, OF CHICAGO, ILLINOIS.

DESIGN FOR A VACUUM CLOTHES-POUNDER.

45,308.

Specification for Design.

Patented Feb. 24, 1914.

Application filed March 1, 1913. Serial No. 751,655. Term of patent 7 years.

To all whom it may concern:

Be it known that I, FRED I. NELSON, a citizen of the United States, residing at Chicago, in the county of Cook and State of Illinois, have invented a new, original, and ornamental Design for Vacuum Clothes-Pounders, of which the following is a specification, reference being had to the accompanying drawings, forming part thereof.

The figure is a perspective view of a vacu-

um clothes pounder, showing my new design.

I claim:

The ornamental design for a vacuum clothes pounder, as shown.

FRED I. NELSON.
